UNITED STATES PATENT OFFICE.

ARTHUR E. SMITH, OF LOS ANGELES, CALIFORNIA.

AMPUL.

Application filed February 15, 1927. Serial No. 168,296.

This invention relates to a drug handling means.

The general object of this invention is to provide a novel means and method for mixing and handling a drug.

A specific object of the invention is to provide a method and means for mixing a drug with a vehicle wherein the drug and the vehicle are contained in independent containers 10 and wherein the containers are placed in communication and the solid made without contact with the atmosphere.

Another object of the invention is to provide separate drug and vehicle containers or 15 ampules wherein the drug and vehicle are each hermetically sealed and wherein means is provided for transferring the vehicle from its container to the drug container.

A further object of the invention is to provide drug preparing means comprising containers having the ingredients therein and having means thereon enabling the containers to be connected.

Another object of the invention is to provide a double ended ampul of the class described which is made of glass and wherein the article contained therein is hermetically sealed at one end by means of a frangible diaphragm portion and wherein the diaphragm portion is sealed from the atmosphere and wherein the other end of the container has means thereon for engaging a delivery tube.

A further object of the invention is to provide an improved means for connecting two containers.

Still another object of the invention is to provide a hermetically tight means for connecting with two containers to enable the containers to be connected and placed in communication.

Other objects and advantages of the invention will be apparent from the following description taken in connection with the accompanying drawings wherein:

Fig. 1 is a central longitudinal section of a drug containing ampul.

Fig. 2 is a view of a vehicle containing ampul.

Fig. 3 is an enlarged fragmentary sectional view showing one end of an ampul and the frangible hermetic seal and the air tight plug.

Fig. 4 is an enlarged fragmentary sectional view showing an ampul end and the hermetic seal formed of the same material as the body 55 of the ampul.

Fig. 5 is a view showing the method of and means for transferring the contents of one ampul to another.

Fig. 6 is an enlarged fragmentary central longitudinal section of the connecting device. 60

Fig. 7 is an enlarged central longitudinal section of the connecting member.

Fig. 8 is a side elevation partly in section showing the mixed solution in the ampul together with an apparatus for supporting the 65 ampul and injecting the solution.

Fig. 9 is a top view of the ampul support and an ampul mounted therein.

Fig. 10 is a modified form of vehicle containing ampul. 70

Fig. 11 shows a modified form of ampul and means of transfer.

Fig. 12 is a section through the hose and one of the clamps shown in Fig. 11.

Fig. 13 is a side view of a clamp showing 75 the handle in section.

Fig. 14 shows another apparatus for applying a vehicle to the drug containing ampul, and

Fig. 15 is a view of a bottle, partly in section, which is adapted to have its contents transferred to a drug containing ampul. 80

Referring to the drawings by reference characters I have indicated my improved drug containing ampul at 10 and my improved vehicle containing ampul at 11. 85

In the following description, although I refer to the containers as ampules, I wish it to be distinctly understood that my invention applies to containers and receptacles in general and is not limited to the particular construction or for the particular purposes which I will hereinafter describe. 90

The drug containing ampul 10 as shown in Fig. 1 comprises a hollow tubular body 12 of 95 glass having a reduced tip 13 at one end thereof and a reduced neck 14 at the other end thereof. The tip 13 includes a bulbous portion 15 wherein a portion of sterile gauze 16 is contained and a closed end portion 17. The bulbous portion 15 and the closed end 17 are preferably separated by a reduced portion 18. The neck 14 includes a bulbous portion 19 and a throat 20 being separated from the bulbous portion 19 by a reduced annular groove 21. 100

Within the throat 20 a thin diaphragm 22 of metal or other material is provided which is preferably fused to the material of the throat 20. Also within the throat 20 a plug 23 is provided which tightly engages the in- 110

ner walls of the throat and forms a hermetic seal. The body 12 of the ampul 10 contains a drug 24, and the interior of the body 12 may be exhausted to form a partial vacuum before the end 17 of neck 14 is closed.

The drug contained in the body 12 of the ampul 10 may be of any character, for instance, salvarsan, neo-salvarsan, sulphorspe-
namine, sodium iodine, etc.

10 The vehicle containing ampul 11 is similar to the drug containing ampul 10 in that it comprises a glass body 25 having a reduced neck 26 formed at one end thereof, but the other end is not provided with a reduced tip
15 such as the tip 13 of ampul 10, it being preferably finished off smooth although both ampules may be alike.

The neck 26 of ampul 11 includes a bulbous portion 27 and a throat 28 separated from 20 the bulbous portion 27 by a reduced annular groove 29. The throat 28 is also hermetically sealed by a metallic partition 30 fused to the inner surface of the throat and is hermetically sealed by a plug 31. A vehicle 25' 25 which may be distilled water is contained in the body 25 of the vehicle containing ampul 11.

The plugs 23 and 31 are preferably made of rubber and are preferably, before insertion 30 into the throats, of a greater diameter than the interior diameter of the throats. In Fig. 3 I have indicated the plug 23 in full lines in the ampul and in dotted lines show its normal size before insertion into the throat 20 of ampul 10.

As shown in Fig. 4 the frangible hermetic partition across the interior of the throat may be formed of the same material as the throat. In this particular instance the ampul 33 is shown as formed of glass and has a neck 34 formed at one end thereof. The neck 34 includes a bulbous portion 35 and a throat 36 separated from the bulbous portion 35 by an annular groove 37. A glass partition 38 across the interior of the throat 36 forms the hermetic seal while a rubber stopper or plug 39 disposed within the throat forms an air tight seal.

I have indicated the connecting device 50 which I now prefer to use in conjunction with the foregoing ampules at 40 in Figs. 5, 6 and 7. The connector 40 comprises a bulbous body portion 41 preferably made of rubber and having projecting circular bosses 55 42 formed thereon. Circular flanges 43 integral with the body 41 are formed around and in spaced concentric relation to the bosses 42. The bosses 42 are slightly tapered outwardly from the body 41 towards their ends, while 60 the interior surfaces of the flanges 43 have a reverse taper to form a slightly V-shaped annular recess 44 between the bosses and the flanges.

A hollow cylindrical tube 45 having bevelled ends 46 is shown as molded in the body

41 and the bosses 42 of the connector 40. The tube 45 has an enlarged knurled portion 47 between its ends. The beveled ends 46 are shown as projecting beyond the ends of the bosses 42.

70 In practice, when an operator desires to mix a solution for use, the connector 40 is used to transfer the vehicle from its container or ampul to the drug containing ampul as shown in Figs. 5 and 6. The device 40 is usually first applied to the vehicle ampul 11 so that the boss 42 fits tightly within the throat 28 and the flange 43 fits tightly over the outer surface of the throat. As the device 40 is placed in position on the throat 28 of ampul 11, the tube 45 first penetrates the seal or plug 31 and then it fractures and penetrates the diaphragm 30. The taper of the recess 44 of the device 40 is such that it forms an hermetic seal between the device 40 and the throat of the ampul 11 prior to the fracturing of the hermetic seal 30.

75 After the metallic partition 30 of the vehicle containing ampul 11 is fractured the throat 20 of the drug containing ampul 10 is placed in the other recess 44 of the connector 40 and the tube 45 is moved to first penetrate the plug 23 and then fracture and penetrate the hermetic seal 22.

80 In Fig. 6 I have shown the tube 45 in a position prior to fracturing the metallic partition 22, in which position the boss 42 and the flange 43 have formed an hermetic seal between the connector and the throat 20 of ampul 10. As the interior of the drug containing ampul 10 has been exhausted so that a partial vacuum exists therein, the vehicle or distilled water contained in ampul 11 will, after the metallic partition 22 has been fractured, be drawn through the hollow tube 45 85 into the body 12 of ampul 10. Thus a solution is formed which is sterile and which is immediately ready for injecting purposes.

90 Various methods and apparatus for injection may be employed with my invention, but I prefer the gravity method. When the solution is to be injected by means of a hypodermic syringe the needle of the syringe may be caused to penetrate the rubber plug 23 and extend through the fracture in the metallic 95 partition 22 into the body of ampul 10 and then upon an actuation of the syringe the whole or a part of the mixed solution in ampul 10 may be withdrawn into the syringe.

95 When the gravity method is used (see Fig. 120 8) the closed end 17 of ampul 10 is fractured and broken off at the restricted portion 18 and then the throat 20 of neck 14 is fractured and broken off at the annular groove 21 after which a rubber cap 50 is placed over 125 the bulbous portion 19. The ampul 10 is then placed in a holder with the bulbous portion 15 directed downward. The holder preferably consists of a metal strip 52 having a bottom rest 53 formed thereon and positioning 130

arms 54 secured intermediate the length of strip 52, and a hook member 55 secured to the upper end of strip 52 by which the holder 51 may be suspended from an object 56.

5 After placing the ampul 10 in the holder 51 a flexible tube 57 is then arranged over the bulbous portion 15. This flexible tube of rubber is connected in any desired manner with a needle 58 for injection. In the accompanying drawings I have shown the connection as including a transparent glass tube 59 containing a quantity of sterile gauze, a rubber tube 60, a second transparent glass tube 61, and another rubber tube 62, although it 10 will be understood that other means of connection may be employed.

When the operator is ready to inject the solution contained in ampul 10 the rubber cap 50 is removed and then the solution will 20 flow through the gauze 16 in the bulbous portion 15 and through the flexible tube 57 to the needle 58. Any fragments of glass or other solid matter will be filtered out of the solution as it passes through the sterile gauze 25 16 in the bulbous portion 15 and the gauze in the transparent glass tube 59.

A modified form of vehicle containing ampul is shown in Fig. 10 and indicated generally at 64. This ampul is similar to the vehicle 30 containing ampul 11 previously described except that it does not contain the metallic partition but is hermetically sealed by a tip formed of the same material as the ampul. The ampul 64 comprises a hollow body 65 finished plain at one end and having a reduced neck 66 provided at its other end. The neck 66 includes a bulbous portion 67, a throat 68, and a closed tip 69 separated from the throat by a restricted annular groove 70. 40 A rubber stopper or plug 71 similar to the plug 31 of ampul 11 is provided in the throat 68. In using this ampul 64 the closed tip 69 is broken off at the annular groove 70 and the tube of a transfer device is caused to penetrate the rubber plug 71 in the same manner 45 as described in connection with ampul 11.

In Fig. 11 I have shown another means for separately holding a drug and its vehicle and for mixing the two. The drug and vehicle holding means is shown as consisting of 50 two glass ampules 72 and 74. The drug containing ampul 72 consists of a hollow body 73 having a reduced tip 75 formed at one end thereof and a reduced neck 76 formed at the 55 opposite end thereof. The tip 75 includes a bulbous portion 77, and a closed end portion 78 separated from the bulbous portion 77 by a restricted annular groove 79. The neck 76 includes a bulbous portion 80 and a closed 60 tip 81 separated from the bulbous portion by a restricted annular groove 82.

The bulbous portion 80 is adapted to contain a quantity of sterile gauze or other suitable filtering material. A predetermined 65 quantity of a suitable drug is placed in the

body 73 of the ampul 72 before the end 78 is closed and the ampul may also be exhausted and a partial vacuum formed therein before the end 78 is closed.

The vehicle containing ampul 74 consists 70 of a body 83 finished plain at one end and having a reduced neck 84 provided at the other end thereof. The neck 84 includes a bulbous portion 85 and a closed tip 86 separated from the bulbous portion by a restricted 75 annular groove 87. A vehicle such as distilled water is placed in the body 83 of ampul 74 before the tip 86 is closed.

When the operator desires to mix a solution one end of a rubber tube 88 is placed 80 over the bulbous portion 80 of the neck 76 on ampul 72 and the other end is placed over the bulbous portion 85 of the neck 84 on ampul 74.

The rubber tube 88 is adapted to be re- 85 tained in air tight engagement with the ampules 72 and 74 by means of clamps 89 placed over each end of the tube between the bulbous portions of the ampules 72 and 74, and their body portions. 90

To cause the vehicle to mix with the drug the rubber tube 88 is grasped so that by the proper movement of the fingers of the operator the tips 86 and 76 will be fractured and parted from the bulbous portions 80 and 85 95 at the annular grooves 82 and 87. After the tips 76 and 86 have been broken off the vehicle will, on account of the exhausted condition of ampul 72, be drawn into the body 73 of the drug containing ampul 72. The gauze in 100 the bulbous portion 80 of ampul 72 prevents any fragments of glass from entering the body 73 of the drug containing ampul.

To remove the mixed solution in ampul 72 for either syringe or gravity injection, the 105 rubber tube 88 is first removed and then the closed end 78 is fractured and broken off at the annular groove 79. The same method of gravity injection may then be employed as shown in Fig. 8 and described in connection 110 therewith.

The clamps 89 used in connection with the method shown in Fig. 11, are shown in detail in Figs. 12 and 13 as comprising a bent metal portion 90 adapted to clamp around the 115 rubber tube 88 and a portion of an ampul, and a rubber handle 91, but it will be understood that any suitable form of clamp may be employed.

In Fig. 14 I have shown another method 120 of mixing the vehicle with a drug contained in an ampul 92. The ampul 92 shown in this figure is similar to ampul 10 shown in Fig. 1, and for the detailed construction of the same the first part of this specification may be referred to.

In this method the vehicle, such as distilled water, is contained in a bottle 93 which may be of any type having a neck 94 thereon. 125 A rubber tube 95 is placed over the neck 94 130

of the bottle and clamped thereto to form a fluid tight connection by a clamp 96. The clamp 96 may be of the same construction as the clamps shown in Figs. 12 and 13, only larger. The rubber tube 95 has an injector 97 provided on its free end which is provided with a hollow tube or needle 98. The construction of this injector 97 may be the same as the connector 40 shown in Figs. 6 and 7, 10 to form an hermetic seal between the connector and the ampul before the needle penetrates the seal and fractures the hermetic seal or metallic partition of the ampul.

When the needle 98 fractures the metallic 15 partition of the ampul 92 the vehicle will be drawn into the ampul by the partial vacuum therein. A clamp 99 of any suitable type is provided on the tube 95 adjacent the injector 97 for controlling the amount of water desired in the ampul 92.

In Fig. 15 I have shown a bottle 100 which may be of any desired capacity and which is provided with means for removing its liquid contents therefrom and transferring it 25 to an ampul of the type shown in Fig. 1. This bottle 100 has a hollow cylindrical neck 101 provided adjacent its lower end which communicates with the interior of the bottle by means of a reduced passage 102. In the 30 hollow of neck 101 and adjacent the passage 102 a rubber plug 103 is provided. The plug 103 is normally of a greater diameter than the inside diameter of the neck 101 and inserted in the neck and retained therein in a 35 compressed state. The plug 103 may be maintained sterile by a quantity of sterile cotton or gauze 104 inserted in the neck 101 and a rubber cap 105 may be provided to fit over the neck.

40 The contents of the bottle 100 such as distilled water may also be protected by a quantity of sterile gauze or cotton 106 inserted in the neck of the bottle.

When an operator desires to transfer a 45 quantity of distilled water contained in the bottle to an ampul the cap 105 and the gauze or cotton 104 are removed from the neck 101 and a connector similar to the connector 40 shown in Figs. 6 and 7 is positioned on the 50 neck so that the hollow tube of the connector will penetrate the rubber plug 103 and at the same time form an hermetic seal between it and the neck 101. After the connector has been positioned on the neck 101 the other end 55 of the transfer device is applied to a drug containing ampul and the distilled water is drawn into said drug containing ampul as previously set forth.

60 By employing separate containers for the drug and vehicle and by providing these containers of different sizes and with different amounts of ingredients therein I am enabled to quickly prepare solutions of various strength.

65 From the foregoing description it will be

apparent that I have provided a novel method and apparatus for storing drugs and their vehicles in separate containers and for mixing the drugs and their vehicles wherein the ingredients remain sterile and wherein simplicity of operation and efficiency are obtained. 70

What I claim is:

1. In combination, an ampul having a drug therein, an independent ampul having a vehicle for said drug therein, both of said ampules being hermetically sealed with respect to each other and to the outside atmosphere, means independent of said ampules connecting the same and including a passage 75 way for the vehicle whereby the contents of the vehicle ampul may be conveyed to the drug ampul when the seals between the ampules and the means are broken, the seal with respect to the outside atmosphere remaining 80 intact.

2. The combination of two ampules, one ampul containing a drug and the other a vehicle for said drug, the contents of both of said ampules being hermetically sealed there- 90 in, one of said ampules having a frangible wall, and a connector for conveying said vehicle from said vehicle ampul to said drug containing ampul, said connector having means thereon for engaging each ampul and having additional means for piercing said frangible wall after the ampules are connected. 95

3. An ampul comprising a container having a neck at one end, said neck including a bulbous portion, said neck having a seal there- 100 in exterior of said bulbous portion.

4. An ampul having a neck at each end, each of said necks including a bulbous portion and one of said necks having a seal there- 105 in exterior of said bulbous portion, said seal being readily frangible.

5. The combination of a container having a drug therein and a container having a vehicle for said drug and a connector connecting said containers, said connector engaging said containers to form an hermetic seal, one of said containers having a frangible seal thereon adapted to be broken to enable the 110 drug and vehicle to mix.

6. The combination of two separate containers, each having a neck thereon and one of said necks having a seal and a connector, said connector engaging said necks in fluid 115 tight engagement, said connector having means thereon adapted to penetrate said seal while in engagement with both of said containers.

7. The combination of a pair of separate ampules, one of said ampules having a drug 125 therein and the other ampul having a vehicle for said drug therein, the contents of said drug containing ampul being sealed therein and the ampul exhausted and a connector for conveying said vehicle from said vehicle am- 130

- pul to said drug ampul, said connector being adapted to engage said vehicle ampul in air tight engagement, said connector having means thereon adapted to penetrate said seal 5 of said drug ampul and to engage said drug ampul in air tight engagement prior to the penetrating of said seal of said drug ampul and while it is in engagement with said vehicle ampul.
- 10 8. The combination of two ampules each having a neck sealed by a penetrable rubber stopper and by a frangible metallic partition, said rubber stopper being contained in said ampules in a compressed state and said metallic partitions being fused to said ampules,
- 15

one of said ampules being exhausted, a transfer means for placing said ampules in communication, said transfer means including a resilient rubber portion adapted to engage said necks and a transfer tube, said transfer tube being adapted to penetrate said rubber stopper, and also being adapted to fracture said metallic partition, said rubber portion of said transfer device being adapted to form a substantially air tight joint with said necks 20 prior to the fracturing of said hermetic seals of said ampules by said tube.

In testimony whereof, I hereunto affix my signature.

ARTHUR E. SMITH.
